UNITED STATES PATENT OFFICE.

GEORGE A. BOWEN, OF MEDINA, NEW YORK, ASSIGNOR, BY MESNE ASSIGNMENTS, TO S. A. COOK & CO., OF SAME PLACE.

FURNITURE.

SPECIFICATION forming part of Letters Patent No. 651,228, dated June 5, 1900.

Application filed January 16, 1900. Serial No. 1,620. (No model.)

To all whom it may concern:

Be it known that I, GEORGE A. BOWEN, a citizen of the United States, residing at Medina, in the county of Orleans and State of New York, have invented certain new and useful Improvements in Furniture, of which the following is a specification.

My invention relates to furniture; and it consists of improvements applicable to furniture having two parts or sections which are hinged together and are adapted to occupy at different times different positions or angular relations one to the other; and it has for its object to provide means whereby such connected or hinged parts of the article of furniture to which the invention is applied may be held in the different positions to which it is desirable to adjust the parts and whereby the said parts may be adjusted from one position to another without it being necessary to have direct access to the means which hold them in the desired positions of adjustment.

For a better understanding of my invention I have shown it applied to two different articles of furniture, the first article being a sofa-bedstead and the other a sofa or couch having a swinging head-rest.

In the drawings, Figure 1 is a vertical section of a sofa-bedstead embodying my improvements, taken on the line 1 1 of Fig. 2, the parts being in position to constitute a sofa. Fig. 2 is a top plan view, partly in section, of the article when the parts are arranged in position to constitute a bed, but one end of the article being shown. Fig. 3 is an enlarged perspective view of one form of a ratchet or catch plate constituting one feature of my invention. Fig. 4 is a vertical sectional view of a sofa having a swinging headpiece to which my invention is applied. Fig. 5 is a top plan view of one end of the same. Fig. 6 is a detached perspective view, enlarged, of the catch or ratchet plate shown in Figs. 4 and 5. Fig. 7 is a top plan view, enlarged, of a ratchet-plate and pawl embodying certain features of construction not shown in the other views.

The sofa-bedstead illustrated in Figs. 1 and 2 is in its main features of construction of a type well known. Referring to these views,

1 designates the end pieces of the stationary frame, and 2 the base. In the end pieces there are formed two grooves, a vertically-disposed groove 3 near the rear edge and a horizontally-disposed groove 4 in the lower forward portion of the end pieces. The sliding or movable sections 5 and 6 are hinged together at 7 and are arranged between the end pieces 1 and above the base-frame 2. They are suitably upholstered, though the upholstery is not represented in the drawings for the sake of clearness, and the section 6 constitutes the upright back when the parts are arranged to form a sofa, and the forward section 5 constitutes the seat. When the parts are arranged to serve as a bed, as shown in Fig. 2, the section 5 is slid forward, and the section 6 is slid downward, and into a horizontal position in rear of the section 5, as is common in this type of bed and need not be described in detail. The rear section 6 is provided at its opposite ends with studs or pins 8, arranged so as to move in the grooves 3, and the lower or forward section 5 is likewise provided with studs or pins 9, adapted to move in the grooves 4. These studs, in connection with the grooves in which they move, serve to give proper direction to the sections when moved from one position to another.

In furniture of this type it is desirable that provision should be made for holding the two upholstery-carrying sections 5 and 6 securely in the relative position which they should occupy in order to constitute a sofa and also for so uniting them that the two sections may be easily shifted from the position shown in Fig. 2 to that shown in Fig. 1, and I will now describe the means which I have invented for so uniting these two sections.

10 represents a pawl or catch loosely pivoted, as at 11, to one of the sections, preferably the upper one. The outer curved end 9' of this pawl is adapted to engage with a catch or ratchet plate or member 12, secured to the other section 5. I prefer that there should be one of the pawls 10 at each end of the section and of course a catch-piece for each pawl to engage with. I prefer that the catch-plates 12 should be arranged close to

the end pieces 13 of the section 5 and that the pawls should extend through openings 12 in the rear frame-piece 14 of the section.

In using my invention in connection with a sofa-bed I prefer to employ the form of catch or ratchet piece represented in Fig. 3. It consists of a plate or base adapted to be secured to a suitable part of the movable section, such plate or base-piece being surrounded by a circumferential flange 15. 16 represents a flange or rib which is arranged substantially midway between and parallel with the opposite sides of the peripheral flange 15 and which operates to divide the catch or ratchet piece into two tracks 17 and 18. The flange 16 is not so long as the base-plate and is so disposed that there are crossways 19 and 20 between the tracks at the opposite ends of the flange. The bent or free engaging end of the pawl 10 is arranged to move in the tracks and ways just referred to, the walls or flanges 15 and 16 confining the pawl and directing its movement. The wall or flange 15 may be cut away at one end, as represented at 21, to permit free engagement of the pawl with the ratchet or catch piece, if this be found desirable. Near one end of one of the tracks 18 there is formed a shoulder 22, with which the end of the pawl 10 is adapted to engage when the parts are in the position represented in Fig. 1. For the sake of convenience in description I will term that end of the ratchet or catch piece which is nearest the shoulder 22 as the "rear" end, the opposite end being of course the forward or front end. The bottom or floor of the way 18 gradually inclines upward from front to rear in order that the pawl may easily ride over the projection 22 and fall behind the same. The way 20 leading from the track 18 behind the shoulder 22 to the track 17 inclines downward and the way 19 leading from the track 17 to the track 18 likewise inclines downward. In order to give the proper inclination to the way 19, I prefer that the bottom or floor of the track 17 should incline upward somewhat toward the rear.

It will be observed that the peripheral flange or bounding-wall 15 opposite to the crossover-ways 19 and 20 is so curved or inclined that it will operate to shift the pawl across from one track to the other if force be applied to the pawl to push or thrust its nose or end against such inclined flange or wall.

As has been stated, when the parts are in the position as represented in Fig. 1—that is to say, with the two sections 5 and 6 at substantially right angles to each other—the end or nose of the pawl lies behind the shoulder 22. There is thus constituted a lock for holding the parts in this position, the position they have when the article is serving as a sofa, for it is evident that any movement of the parts tends to carry them from the position shown in Fig. 1 to that shown in Fig. 2 which would result in moving the pawls forward, and such movement is resisted by the shoulders 22. When, however, it is desired to shift

the parts and move them into the position shown in Fig. 2, so as to constitute a bed or couch, it is only necessary to lift the forward edge of the lower section a little. This movement will cause the pawls to move backward in the track 18 beyond the ends of the mid-rib 16 and upon the inclined ways 20, and as soon as this occurs the ends of the pawl will slide down the ways 20 and into the tracks 17, this lateral movement of the pawls being permitted by reason of their being loosely pivoted or mounted at 11. The pawls now being in the tracks 17, which are free from their rear to their forward ends, the sections may be moved into the position shown in Fig. 2. Just before the parts reach the position indicated in this view the ends of the pawls pass from the tracks 17 beyond the ends of the mid-rib 16 and onto the ways 19, down which they slide into the track 18, as represented in Fig. 2. When it is desired to fold up the parts, shifting them from the position shown in Fig. 2 to that shown in Fig. 1, it is only necessary to lift the forward end of the front section 5 until the two sections assume a position substantially at right angles to each other, when the pawls will have moved rearward to a position behind the shoulders 22. The sections being then locked together, they may be moved into the Fig. 1 position by simply pressing down and backward upon the front edge of the lower section.

23 indicates a spring connection between the rear portion of the bottom frame 2 and the lower or front piece of the upper frame. This part operates when this section is being lowered to prevent it from falling to its lower position with undue violence and also assists in restoring the parts to their folded position.

24 represents a sliding pin preferably mounted in the upper portion of the sliding section 6 and so arranged that when the parts are in position to constitute a sofa it may be moved so as to engage with the groove 3. It thus serves as a lock to prevent shifting of the parts so long as it remains in engagement with the slot or groove 3.

Referring now to Figs. 4 to 6, where my invention is represented as being applied to a sofa or couch having a swinging headpiece, 5' represents the main or body portion of the couch, and 6' the swinging head-section. These two portions are united by suitable hinge connections 7'. Arranged between the main frame portion of the couch and the head-section are the pawl-and-ratchet parts, substantially similar to the parts which have before been described as arranged between the sections 5 and 6 of the sofa-bed. 10 designates the pawl, pivotally connected at 11 with the swinging head-section of the couch. 12 designates the ratchet or catch device. Referring particularly to Fig. 6, it will be observed that this part consists of a plate adapted to be secured to a suitable part of the frame of the couch, having a circumferential flange 15 and a mid-rib or flange 16, on either side of

which are formed tracks for the passage of the nose or end of the pawl and at the ends of which are the crossover-ways 19 and 20. The only material difference between the device represented in Fig. 6 and that in Fig. 7 is that in the form of the invention shown in Fig. 6 the bottom or floor of the track 18 is formed with a series of projections in the form of ratchet-teeth 25, arranged between the forward end of the catch-plate and the rear projection 22. This permits the adjustment of the head-section to as many different angles as there are ratchet-teeth with which the pawls may engage.

15 It will be seen that the pawls automatically shift from one track to the other by gravity as the sections are moved from one extreme of movement or position to the other. Should it be found desirable, however, to supplement the action of gravity in causing the pawl to move from the track 18 to the track 17, I may employ a spring, such as 26, Fig. 7. This, however, would not usually be necessary.

25 It is sometimes desirable in articles of the character such as I have described to be able to adjust the parts without first moving them to an extreme position. Supposing the head-section of the couch to have been given but a slight inclination as by reason of the engagement of the pawls with the foremost ratchet-teeth, it may be desirable to restore it to a horizontal position without first increasing its inclination. To permit this, I provide means whereby the pawl may be operated by hand from the side of the couch. 27 is a rod connected with the pawl and extending outward to one side of the couch, where it is provided with a handpiece 28. By lifting the pawl so as to clear the ratchet-teeth 25 the head-section 6' may be lowered from any position.

35 Where a pawl-and-ratchet device such as I have described is provided at each side of the couch, which is the preferred arrangement, the rod 27 should extend across the couch so as to unite the two pawls that they may be operated simultaneously.

45 The connecting hinge-pieces 7', which unite the parts 5' and 6', may be provided with stop-lugs arranged to prevent the swinging section from being turned to too great an angle relative to the main portion of the couch. I thus prevent danger of the pawls being carried backward so far as to entirely disengage the catch or ratchet pieces 12.

55 It will be understood that I have represented the pawls and the ratchets with which they engage as being larger in proportion to the other parts shown than they are in actual practice. This has been done in order that the invention may be more clearly brought out in the drawings.

It will be observed that in both forms of the invention shown there are two portions or sections of furniture which are united by hinge connections and are adapted to move to change their angular relations to each

other and that there are combined with such furniture - sections means for holding the parts securely in a desired angular relation to each other without, however, preventing them from being moved into a position beyond the desired position, means for disengaging the said holding parts when the sections of the article of furniture are moved beyond the desired position, means for maintaining the said holding parts disengaged while the sections of the article are being moved to a second desired position, and also means for bringing the holding parts into operative engagement when the sections of the article are being moved from their last said position to the first-referred-to position, and that these means operate automatically, so that they may be entirely concealed by the casing or framework of the article.

Having described my invention, what I claim, and desire to secure by Letters Patent, is—

1. In furniture, the combination with two hinged parts or sections, of a pawl or catch carried by one of the parts, the said pawl having a certain amount of lateral movement, and a catch or ratchet plate carried by the other section provided with two tracks in one of which tracks is formed a projection with which the pawl is adapted to engage, and means for shifting the pawl laterally from one track to the other, substantially as set forth.

2. In furniture, the combination with two sections hinged together, of a pawl carried by one section and a horizontally-arranged catch or ratchet plate carried by the other, the said catch-plate being formed with two separated tracks arranged side by side in which the end of the pawl is arranged to move, crossover-ways at the ends of the tracks inclining downward in opposite directions, and a projection with which the pawl engages near the rear end of one of the tracks, arranged a little in advance of the crossover-way at such end, substantially as set forth.

3. In a sofa-bed, the combination with a supporting-frame provided with the grooves 3 and 4, a section arranged to constitute the back of the sofa and another section hinged thereto arranged to constitute the seat of the sofa, studs carried by the said sections and arranged to travel in the said grooves, catch devices for holding the sections when in position to constitute a sofa and preventing them from changing their angular relations, and a sliding pin or stud 24 carried by the back-section and arranged to be moved into engagement with the groove 3 and thereby prevent the shifting of the parts or sections of the sofa-bed, substantially as set forth.

4. The combination, in furniture, with two sections hinged to each other, one of which is arranged to move relative to the other to change their angular relations, of a pawl having a certain amount of lateral movement carried by one of the parts or sections, and a

catch or ratchet plate carried by the other, the said ratchet-plate being formed with two longitudinal, separated, tracks in which the pawl is arranged to move, one of the tracks 5 being provided with a series of projections with which the end of the pawl engages to hold the sections in different angular relations to each other, the ratchet-plate being also provided with an inclined crossover-way 10 between the tracks in rear of the last of the said series of projections, and with another crossover-way oppositely inclined to the said first-mentioned crossover-way and arranged in front of the series of projections, substantially as set forth.

5. In furniture, the combination with two sections hinged together, of a pawl carried by one of the sections and a horizontal catch or ratchet plate carried by the other, the said 20 catch-plate being formed with two separate tracks arranged side by side in which the end of the pawl is arranged to move, crossover-

ways at the ends of the tracks, and inclined or curved flanges or walls opposite the said crossover-ways with which the end or nose 25 of the pawl is adapted to engage, substantially as set forth.

6. In furniture, the combination with two sections hinged together, of a pawl carried by one of the sections and a catch or ratchet 30 plate carried by the other, the said plate being surrounded by a peripheral flange and formed with two separated tracks in which the end of the pawl is arranged to move, crossover-ways at the ends of the tracks, a fixed 35 separating rib or flange between the tracks, and a projection with which the pawl engages near the rear end of one of the tracks, substantially as set forth.

GEORGE A. BOWEN.
